Norman N. Hekler, High Point, N.C., assignor to Worth Furniture, a division of Gravely Furniture Co., Inc., Martinsville, Va., a corporation of Virginia

Filed Mar. 26, 1963, Ser. No. 74,136

Term of patent 3½ years

(Cl. D33—19)

FIG. 1.

FIG. 2.

FIG. 3.

FIG. 1 is a top plan view of a chest showing my new design;

FIG. 2 is a front elevational view thereof; and

FIG. 3 is a side elevational view of the same.

The appearance and configuration of the side of the chest opposite the side shown in FIG. 3 is substantially the same as that shown while the back is plain and unornamented.

I claim:

The ornamental design for a chest, as shown and described.
